UNITED STATES PATENT OFFICE.

ADAM L. HUYLAR, OF KEYPORT, NEW JERSEY.

PLAITING-MACHINE.

1,188,275.

Specification of Letters Patent. Patented June 20, 1916.

Application filed November 17, 1914. Serial No. 872,611.

To all whom it may concern:

Be it known that I, ADAM L. HUYLAR, a citizen of the United States, residing at Keyport, in the county of Monmouth and State of New Jersey, have invented new and useful Improvements in Plaiting-Machines, of which the following is a specification.

The invention relates to a plaiting machine, and more particularly to the class of machines for plaiting rubber bathing caps.

The primary object of the invention is the provision of a machine of this character wherein a blank of rubber material can be placed in the same so that on operating the machine the material will be plaited for the formation of the bathing cap.

Another object of the invention is the provision of a machine of this character wherein the construction thereof is of novel form to permit easy and quick operation of the same and also to insure the uniform plaiting of the cap body when being made during the working of the machine.

A further object of the invention is the provision of a machine of this character which is simple in construction, thoroughly reliable and efficient in operation, strong, durable, and inexpensive in manufacture.

With these and other objects in view, the invention consists in the construction, combination and arrangement of parts as will be hereinafter fully described, illustrated in the accompanying drawings, and pointed out in the claims hereinafter appended.

In the drawings:—Figure 1 is a side elevation of a machine constructed in accordance with the invention. Fig. 2 is a top plan view thereof. Fig. 3 is a vertical longitudinal sectional view thereof. Fig. 4 is a sectional view on the line 4—4 of Fig. 3. Fig. 5 is a sectional view on the line 5—5 of Fig. 1. Fig. 6 is a perspective view of one of the plaiting arms. Fig. 7 is a perspective view of the sleeve for moving and clamping the pivoted plaiting arm.

Similar reference characters indicate corresponding parts throughout the several views in the drawings.

Referring to the drawings in detail, the machine comprises a base 10, preferably made from metal, although the same may be made from any other suitable material, and has rising therefrom spaced opposed uprights 11 supporting a cross head 12, which is fixed thereto in any suitable manner, or made integral therewith, these parts being designed to serve as the frame of the ma-

chine. Mounted centrally on the base is a column 13 formed with an enlarged circular work support 14 having a central circular depression or recess 15 in its upper face to provide concentrically thereof a flange 16 in which are pivoted the swinging plaiting members hereinafter fully described.

The flange 16 is formed at equidistances apart with slots 17 which are radially disposed and receive the inner ends of the swinging plaiting members comprising arms 18, the flange 16 being formed in its outer periphery with a continuous slot 19 for receiving the pivot wire 20 which is passed through the inner ends of the arms 18 for swingingly connecting the same to the support on which is adapted to be placed the circular blank of rubber material to form the body of the bathing cap, the arms 18 being moved for the plaiting of the material in a manner presently described. Fixed in the cross head 12 centrally thereof in any suitable manner and depending therefrom is a hollow stem 21 formed with a disk-like head 22, and on this stem 21 is slidably mounted a disk 23 formed with a collar 24 concentrically about the stem 21, the disk 23 being fitted in its peripheral edge with stationary plaiting arms 25 which are arranged in spaced relation to each other an equal distance apart and depend concentrically about the head 22 to coact with the arms 18 in a manner presently described.

The stem 21 is formed at diametrically opposite points with longitudinal slots 26 through which are passed L-shaped catches 27, the same being slidably mounted at diametrically opposite points in the collar 24, and are acted upon by means of springs 28 which have their outer ends working against heads 30 formed on the catches 27, the springs being designed to hold the catches 27 under tension for locking engagement with toothed racks 31 formed internally of the stem 21 contiguous to the slots 26 therein, and in parallel relation to the same at one side thereof. On pressing inwardly upon the catches 27 the same can be released from the racks 31 so that the disk 23 can be adjusted on the stem 21 for positioning the stationary arms 25 in operative relation to the arms 18 or in inoperative relation thereto.

Slidably on the support 14 and disposed concentrically about the same is a sleeve 32 formed with a flared upper edge 33 which serves as an annular cam for operating the

- movable arms 18 to swing the same upwardly and inwardly in a vertical position between the arms 25 from their normal horizontal position.
5. Integral with or mounted in the sleeve at diametrically opposite points thereof are lugs 34 with which engage the limbs 35 of U-shaped bails 36 which are mounted for sliding movement through the base 10 and 10 are bolted or otherwise connected to a link 37 which is pivotally connected to the inner end of a rocking lever 38 pivoted at 39 to a depending bearing 40 secured to the under side of the base so that on the rocking of 15 the lever 38 the sleeve 32 will be shifted for the raising of the arms 18 to bring the same into operative relation to the stationary arms 25 in the plaiting of the material for the body of the cap.
20. The sleeve 32 normally rests upon stop pins 41 fixed in the support 14 for the work, and the sleeve is in this position when the arms 18 are in a horizontal plane.
- Mounted upon the arms 18 near the outer 25 ends thereof are spring held jaw clips 42 each being formed with a split collar 43 adapted to embrace the arms 18, which is formed with a slot 44 to receive the ring 43 so that the clip 42 will not move longitudinally on the arm, and these clips 42 are 30 adapted to engage the peripheral edge of the circular piece of material when placed upon the support 14, so that on the swinging of the arms 18 upwardly the material 35 will be held for the action of the arms 18 and 25, which will form the plaits therein, the said plaits being made permanent on the subsequent application of the tape to the body of the cap.
40. Slidably mounted on the arms 18 are trip sleeves 45 which are adapted to ride onto the jaws of the clips 42 when the arms 18 have been swung to vertical position, so that the material engaged by the clips will be 45 released, and to effect automatic movement of the sleeves 45 they have connected thereto pull cables 46, the same being connected to tension springs 47 which are suitably mounted on the support 14, the sleeves 45 being normally disengaged from the clips 42, and on the raising of the arms 18 the springs 47 will become tensioned to automatically shift the sleeves 45 onto the jaws of the clips 42 for the automatic releasing 55 of the material after the plaits have been formed therein.
- In the operation of the machine, the circular piece of material is placed upon the support 14 when the arms 18 are in a horizontal plane, and the peripheral edge of this 60 piece is engaged by the clips 42, whereupon the sleeve 32 is raised by operating the lever
- 38, forcing the arms 18 upwardly into vertical position, it being understood of course that the stationary arms 25 on the disk 24 are in lowered operative position so that these arms 18 and 25 will cooperate with each other for the formation of plaits in the material. Now, after the plaits have been thus formed, the material is automatically released by freeing the clips 42 under the action of the collars 45, which are moved by the tensioning of the springs 47 when the said arms 18 have moved to vertical position. After the material has been released, the 75 disk 23 is raised so that the tape can be fixed to the inner surface of the body of the cap to hold the plaits permanent, and thereafter the said arms 18 are permitted to be lowered to a horizontal plane for the subsequent application of the tape at the outer side of the body of the cap, thus producing a finished rubber bathing cap.
- From the foregoing description, taken in connection with the accompanying drawings, the construction and manner of operation of the device will be clearly understood, and therefore a more extended explanation has been omitted.
- What is claimed is:—
1. A plaiting machine of the class described comprising a stationary member, a movable member, plaiting arms fixed to the movable member, movable plaiting arms supported by the stationary member, means for shifting the movable plaiting arms into operative relation to the fixed plaiting arms, means for adjustably supporting the movable member, a work support formed on the stationary member, a frame for the stationary and movable members, and resilient clips on the movable plaiting arms.
2. A plaiting machine of the class described comprising a stationary member, a movable member, plaiting arms fixed to the movable member, movable plaiting arms supported by the stationary member, means for shifting the movable plaiting arms into operative relation to the fixed plaiting arms, means for adjustably supporting the movable member, a work support formed on the stationary member, a frame for the stationary and movable members, resilient clips on the movable plaiting arms, and means for automatically releasing the clips on the raising of the movable arms to vertical position.

In testimony whereof I affix my signature in presence of two witnesses.

ADAM L. HUYLAR.
